UNITED STATES PATENT OFFICE.

BERT A. STOCKING, OF BOONE, IOWA.

FASTENER FOR COVERS OF WASHING MACHINES.

Application filed February 11, 1918. Serial No. 216,461.

To all whom it may concern:

Be it known that I, BERT A. STOCKING, a citizen of the United States, residing at Boone, in the county of Boone, and State of

5 Iowa, have invented certain new and useful Improvements in Fasteners for Covers of Washing Machines, of which the following is a specification.

My invention relates to washing machines, 10 and more particularly to improved means for securing the lid in locked position.

One of the troublesome features in connection with washing machines has heretofore been the loss of time, worry and annoyance caused by the inconvenient arrangement and difficult manipulation of the various forms of locks used to secure the lid in closed position upon the tub. All this is obviated by my new form of lock, to manipulate 15 which all that is necessary is to simply turn the conveniently arranged and readily accessible handle through ninety degrees, which when unlocking results in the locking parts being automatically thrown and held 20 out of engagement, and when locking securely holds the parts in locked engagement.

Among the objects of my invention therefore is the provision of easily manipulated and conveniently arranged means for securely locking the lid of a washing machine 30 in operative position upon the tub; further to provide such means in which by a simple turning of the handle the locking parts will be automatically disengaged; further to so arrange the locking member carried by the lid that after being unlocked it will be positively held in unlocked position until the handle is again turned for locking; further to so construct the handle of the locking 35 means that when turned into locking position the locking parts are positively locked against disengagement; further to provide such form of lock that may be used to lock together any two parts in which one part is 40 arranged for movement toward and away from the other; and further to provide such combination, construction and arrangement of parts as will result in a more simple, economical and efficacious device of the class 45 described.

Further objects and advantages will become apparent as the following description proceeds.

In the drawings, while I have illustrated 55 a preferred embodiment of my invention, I desire it to be understood that the same is

susceptible of modification and change without departing from the spirit of my invention.

Referring to the drawings: 60

Fig. 1 is a transverse vertical cross sectional view of a washing machine embodying my invention.

Fig. 2 is a fragmentary plan view of a portion of the tub, showing my improved 65 form of lock thereon.

Fig. 3 is a view showing the parts of my improved lock in separated position ready to be assembled.

In the drawings, upon the tub 1 is mounted 70 the lid 2, through which extends the shaft 3, which imparts suitable motion to the dasher 4. The tub is surrounded by the usual hoops 5 and 6. Securely locking the lid in position on the tub is my improved 75 form of lock designated generally by A, and which lock is made up as follows: Upon the lid 1 and near one edge thereof is securely mounted the plate 7, and upwardly extending from this plate is the pin 8, upon 80 which is rotatably mounted the handle 9. The portion of the handle immediately surrounding the pin 8 is of elongated formation, the two edge portions 9' of which virtually form cams, the purpose for which 85 will later appear. A suitable head 10 is provided upon the upper end of the pin 8 for the purpose of holding the handle 9 in proper position. The plate 7 is provided with suitable apertures 11 and 12 for securing 90 the same in position upon the lid 2, and at its forward portion is also provided with ears 13 and 14, which are bent upwardly then inwardly to form the slot 15, as clearly shown in Fig. 3. Mounted within this slot 95 15 for longitudinal sliding movement is the latch plate 16, which is provided with the downwardly extending portion 17, upon which is formed the inwardly extending projection 18 which lies in substantially parallel relation to the plate 16. The portion 100 17 has formed therein a suitable socket 19 for the reception of the end of the spring 20, which spring is inserted in the socket 21 formed in the lid 2 and is of such length as 105 to be under compression when the parts are in locking position, and thus exerts an outward thrust on the portion 17 of the sliding latch. It is obvious, of course, that other 110 equivalent means may be employed for holding the outer end of the spring 20 in engagement with the portion 17 of the latch.

if desired, for example, a projection instead of a socket.

Suitably formed in the upper portion of the latch 16 is a slot 22, which slot is adapted to receive the pin 8 and to permit the latch 16 to have a longitudinally sliding movement on said pin. The plate 16 is further provided at its rear portion with the upwardly extending projection 23. Mounted upon the tub portion and adjacent the upper edge thereof is the socket member or angle piece 24, in which is formed the offset portion 25 to fit over the hoop 6. Upon the upper end of the angle piece 24 is an outwardly extending projection 26 of a length substantially equal to that of the inwardly extending projection 18 of the latch 16. The members 24 and 7 are secured to the tub by means of screws, bolts, or other suitable fastening devices.

The operation of my improved lock is as follows: Assuming that the parts are in locked position as shown in Fig. 1 and it is desired to throw them into unlocked position, all that is necessary is to grasp the handle 9 and rotate the same through an angle of ninety degrees, which operation removes the engaged cam 9' away from engagement with the projection 23, thus permitting the latch plate to move forwardly upon the plate 7 under action of the spring 20, which movement automatically disengages the projection 18 of the latch plate from the projection 26 of the socket member or angle piece 24. As long as the handle 9 stands in unlocked position the projection 18 will stand out of engagement with the projection 26, as a result of the continual outward pressure exerted on the portion 17 by the coil spring 20, thus insuring that the locking parts will be completely disengaged until it is desired to again lock the lid on the tub. When it is desired to lock the lid in position on the tub, the handle 9 is rotated through an angle of ninety degrees, which effects the reverse operation of that just described. In other words, this rotation of the handle 9 brings the cam 9' into engagement with the projection 23, thus forcing the latch plate 16 backwardly upon the plate 7 until the projection 18 again engages the projection 26. This movement compresses the spring 20, which compression of the spring holds the projection 23 firmly against the cam 9', and thus insures the handle 9 from jarring loose or being accidentally turned.

It will thus be seen that I have provided a device for securely and quickly locking the lid upon the tub of a washing machine, the operation of which requires nothing further than the mere turning of a conveniently located and easily manipulated handle, which results in the locking parts being positively thrown into locking engagement and so held until unlocking is desired. Also unlocking is accomplished by merely turning the same handle which results in the locking parts being automatically disengaged and thrown away from engagement with each other, and so held until locking is again desired. This arrangement of parts gives the maximum of simplicity, and results in a lock which entirely obviates the bother, vexation, and loss of time heretofore present in the more clumsy and complicated forms of locks. While my improved lock is especially adapted for use in locking the lid of a tub in washing machines, it is, of course, evident that the same may be used in locking together any two parts in which one part swings or similarly moves toward and away from the other.

Having now described my invention,

I claim:—

1. In apparatus of the class described, two members to be locked together, a plate on one of said members, a pin on said plate, a latch having an elongated slot fitting over said pin, ears on said plate bent to overlie said latch, a handle on said pin, a cam on said handle, a projection on said latch adapted to engage said cam, latch-receiving means on the other of said members, and a spring normally pressing said latch in one direction, whereby upon rotation of said handle to unlocked position said locking parts will automatically fly apart, and upon further rotation of said handle said parts will become locked.

2. In apparatus of the class described, two members, one being fixed and the other hinged thereto, an angle plate on the fixed member, a latch slidably mounted upon the other of said members, single means for sliding said latch and holding it in locked position, and further means for automatically disengaging and normally holding apart said latch and angle plate upon suitable manipulation of said single means.

In witness whereof, I hereunto subscribe my name to this specification.

BERT A. STOCKING.
